UNITED STATES PATENT OFFICE.

JAMES HENRY BODDIE, OF SUMPTER, LOUISIANA.

DESIGN FOR A FENCE-POST.

SPECIFICATION forming part of Design No. 30,913, dated May 30, 1899.

Application filed May 1, 1899. Serial No. 715,241. Term of patent 14 years.

To all whom it may concern:

Be it known that I, JAMES HENRY BODDIE, a citizen of the United States, residing at Sumpter, in the parish of Lincoln and State of Louisiana, have invented a certain new and useful Design for a Fence-Post; and I do declare the following to be a full, clear, and exact description of the invention, such as will enable others skilled in the art to which it applies to make and use the same, reference being had to the accompanying drawings, which form a part of this specification.

Figure 1 is a perspective view of a fence-post, showing my new and original design. Fig. 2 is a transverse section of the same.

As shown in the drawings, the leading or material feature of my design consists of a rectangular body portion provided upon one of its sides with a longitudinal slot or depression, within which groove or depression are shown openings or holes extending through the post. The lower end of the post is shown as cut away to form a point; and the post at its upper end is shown as provided with an ornamental design consisting of a pyramid separated from the body portion of the post by a horizontal groove.

Having thus described my design, what I claim to be new, and desire to secure by Letters Patent, is—

The design for a fence-post, herein shown and described.

In testimony whereof I affix my signature in presence of two witnesses.

JAMES HENRY BODDIE.
